BREAKER ARM JIG

Gordon Kells, Auckland, New Zealand

Application April 23, 1943, Serial No. 484,256
In New Zealand March 25, 1942

6 Claims. (Cl. 51—216)

This invention has been devised with the object of providing a jig for use in the adjustment and maintenance of the contact points of the rocker arms of the contact breakers used in the electric ignition systems of various forms of internal combustion engines, at the same time maintaining or correcting the angular relationship between the fixed point, the fulcrum and the heel of the rocker arm.

In the adjustment of these contact points of a rocker arm it is important that the correct relationship of the face of the fixed point, and the face of the heel to the fulcrum upon which the rocker arm rocks and to each other, shall be effected throughout the entire life of the assembly. The jig that forms the subject of this invention provides for the rocker arm being so positioned and held within it that the faces to be renewed or treated may be readily and correctly operated upon by their subjection to appropriate grinding or filing means to automatically obtain the proper relative adjustment with the fulcrum of the rocker arm.

The invention will be described with the aid of the accompanying drawing, wherein:

Figure 1 is a perspective view of the jig.

Figure 2 is a side view.

Figure 3 is a cross section.

Figure 4 is a cross section with a rocker arm in position for setting up one part, and

Figure 5 is a similar view showing the position of the rocker arm when setting up another part.

Referring to the drawing, the jig is formed of a solid metal block 1 of suitable length and of a cross sectional shape providing planar surfaces 2 and 3 extending longitudinally throughout the length of the block and with a rounded or arcuate face 4 on its perimeter forming finishing-element-guiding surfaces, all enclosed within a circle so that the block can be cut from a section of rounded bar steel.

The block is formed with a slot 5 extending transversely inwardly for a distance midway of its length sufficient to bisect the planar faces and also the rounded face 4, leaving a section of metal 6 to connect the two parts of the block. The sides of the slot are parallel and of a width to allow the rocker arm to fit neatly within it. Holes 7 and 8 are provided, being bored longitudinally through the block from end to end. It will be seen that the bottom of the slot 5 lies beneath the finishing-element-guiding surface 2 and is parallel therewith. The remainder of the slot then passes round the block bisecting the part containing the holes 7 and 8 and finally

forming a groove 9 beneath the neck of metal 6 joining the two parts together, the part of the neck at the bottom of the groove 9 forming a stop face 10 against which a point of the rocker will bear when in one position.

A fulcrum pin 11 is provided for passing through the holes 7 and 8 and adapted to be passed through the fulcrum boss of a rocker and so fasten the rocker arm within the slot.

10 In Figure 4 a rocker arm 12 has been placed in one position in the slot and held by the pin 11 being passed through the hole 7 and boss of the rocker, so that the platinum point 13 is held against the face 10, while the composition 15 heel 14 is disposed to the rounded surfacing plane 4 so that this heel can be finished, as by grinding or filing in accordance with the face of the plane in order to renew its surface, the relationship of the hole 7, the face 10, and 20 rounded plane being to ensure the correct angular relationship of the heel to the point.

In Figure 5, the rocker arm is inserted in the slot of the block with its platinum point 13 lying in the slot so that the point is disposed to the 25 surface 2, thus enabling the point to be filed or rubbed by an oilstone in order to reset the point.

The said block faces and the form of the slot and its position in relation to the faces, as well 30 as the positions of the pin receiving holes passing across the slot, may be varied in a number of ways to suit the type of rocker arm to be operated upon. In all instances, however, the same principles of formation of the jig forming 35 block are carried out.

I claim:

1. A jig for positioning and holding rocker arms having contacts which are spaced from and at an angle to each other so that the contacts lie at a given position with respect to a given portion of the jig comprising a block having a plurality of finishing-element-guiding surfaces extending at an angle to each other and a transverse rocker-arm-receiving slot intersecting said surfaces, said block also having holes extending normal to said slot to receive a fulcrum pin, the relative position of said faces to each other and to the holes being such that when a rocker arm is held in said slot by a pin inserted 40 in a selected one of said holes coaxial with the fulcrum point of the rocker arm, the rocker arm will be so positioned that one of said contact points is disposed to one of said finishing-element-guiding surfaces and in correct angular relationship to the other point of the rocker arm.
- 45
- 50
- 55

2. A jig for positioning and holding rocker arms having planar and arcuate contacts which are spaced from and at an angle to each other so that the contacts lie at a given position with respect to a given portion of the jig comprising a block having planar and arcuate finishing-element-guiding surfaces and a transverse rocker-arm-receiving slot intersecting said surfaces, said block also having holes extending normal to said slot to receive a fulcrum pin, the relative positions of said faces to one another and to the holes being such that when a rocker arm is held in said slot by a pin inserted in a selected one of said holes, coaxial with the fulcrum point of the rocker arm, the rocker arm will be so positioned that one of said contact points is disposed to one of said finishing-element-guiding surfaces and in correct angular relationship to the other point of the rocker arm.

3. A jig as set forth in claim 2 in which the planar face is parallel with a face at the bottom of the slot.

4. A jig as set forth in claim 2 in which the arcuate finishing-element-guiding surface extends from each side of the slot so that the arcuate contact of the rocker-arm may align with such arcuate surface, and in which a stop surface for engagement by the planar contact is formed below the neck portion joining the two portions of the block formed by the transverse slot.

5. A jig for positioning and holding rocker arms having contacts which are spaced from and at an angle to each other so that the contacts lie at a given position with respect to a given portion of the jig comprising a block having a plurality of finishing-element-guiding surfaces

extending at an angle to each other and a stop surface, said block also having a rocker-arm receiving slot intersecting the finishing-element-guiding surfaces and a hole extending normal to said slot to receive a fulcrum pin, the relative positions of said surfaces to each other and to the hole being such that when a rocker-arm is held in said slot by a pin coaxial with the fulcrum point of the rocker arm inserted in said hole, with one of said contacts engaging the stop surface, the rocker arm will be so positioned that the other contact point is disposed to the arcuate finishing-element-guiding surface in correct angular relationship to the first mentioned contact point.

6. A jig for positioning and holding rocker arms having planar and arcuate contacts which are spaced from and at an angle to each other so that the contacts lie at a given position with respect to a given portion of the jig comprising a block having an arcuate finishing-element-guiding surface and a planar stop surface, said block also having a rocker-arm receiving slot intersecting the finishing-element-guiding surface and a hole extending normal to said slot to receive a fulcrum pin, the relative positions of said surfaces to each other and to the hole being such that when a rocker arm is held in said slot by a pin coaxial with the fulcrum point of the rocker arm being received within said hole with the planar contact engaging the planar stop surface, the rocker arm will be so positioned that the arcuate contact point is disposed to the arcuate finishing-element-guiding surface in correct angular relation to the planar contact.
